(57) **CLAIM**

(22) Filed: **Jun. 28, 2016**

The ornamental design for an interactive stuffed animal lion
toy, as shown and described.

(51) LOC (10) Cl. 09-01

DESCRIPTION

(52) U.S. Cl.

USPC D21/618

(58) **Field of Classification Search**

USPC D6/598; D11/158; D21/576-585,
D21/587-588, 617-618; D30/160;

446/97, 356, 369-369, 376
CPC ... A63H 3/00; A63H 3/02; A63H 3/06; A63H
3/08; A63H 3/10; A63H 3/16; A63H
3/20; A63H 7/00; A63H 13/00; A63H
11/18; A63H 11/20

FIG. 1 is a front angled view of an interactive stuffed animal

lion toy;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken line showing of the rectangular portion on the
rear of the toy is for the purpose of illustrating an internal
pocket containing electronics required for charging the toy
and forms no part of the claimed design.
